UNITED STATES PATENT OFFICE

143,438

DESIGN FOR AN ARTICLE HOLDING FIGURINE

Vincent I. Mora and Earl Heinecke, Minneapolis,
Minn.; said Heinecke assignor to said Mora

Application April 27, 1945, Serial No. 119,281

Term of patent 14 years

(Cl. D29—23)

To all whom it may concern:

Be it known that we, Vincent I. Mora and Earl Heinecke, citizens of the United States and residing in the city of Minneapolis, county of Hennepin, State of Minnesota, have invented a new, original, and ornamental Design for an Article Holding Figurine, of which the following is a specification, reference being had to the accompanying drawing forming a part thereof, wherein:

Fig. 1 is a front perspective view of an article holding figurine, showing our new design;

Fig. 2 is a back perspective view of the same;
Fig. 3 is a perspective view of the same from one side; and

Fig. 4 is a perspective view of the same from the other side. The receptacle in dotted lines supported by the figurine is for illustrative purposes only.

We claim:

The ornamental design for an article holding figurine, substantially as shown and described.

VINCENT I. MORA.
EARL HEINECKE.
